STAMP SUPPORT AND PAD

Austin C. Johnson and Theodore M. Wroble,
Chicago, Ill.

Application June 14, 1935, Serial No. 26,612

7 Claims. (Cl. 101—333)

Our invention relates to a combination support and inking device for stamps of the same general character as shown in our co-pending application, Serial No. 723,026, filed April 30, 1934.

5 The time required for inking the pad and the desk space occupied by a stamp and ink pad are minimized by superimposing the stamp upon or above the pad and it is frequently the practice to leave the stamp standing upon the pad with 10 the result that the material, such as rubber, forming the characters, is subject to rapid disintegration and the useful life of the characters is thereby shortened. Time stamps providing stationary and clock-actuated rotatable characters lying in 15 the same plane cannot be left standing upon the pad without a tendency to retard the clock movement and render the time stamp inaccurate.

The invention contemplates a support enclosing the pad on all sides except at the top and the 20 use of the stamp as a cover for the pad, thereby not only saving desk space and time necessary to manipulate the stamp but also increasing the useful life of the pad since the stamp provides a dust proof and a substantially air tight cover which 25 prevents drying of the pad by exposure to the atmosphere.

The invention has as one of its objects the provision of a device adapted as a support normally maintaining a stamp positioned thereon with its 30 characters in non-contacting juxtaposition to the pad, the support being yieldable under pressure to permit uniform inking contact of the characters with the pad.

Another object of the invention is the provision 35 of an improved stamp supporting device providing an enclosure for an inking pad, the stamp being adapted as a cover preventing entrance of dust and circulation of air about the pad and the support being yieldable under pressure to permit even contact of the stamp characters with the pad.

A further object of the invention is the provision 40 of a combination stamp support and inking device which is simple, economical, durable and satisfactory for its intended purpose.

Many other objects and advantages of the construction herein shown and described will be obvious to those skilled in the art from the disclosure herein given.

50 To this end our invention consists in the novel construction, arrangement and combination of parts herein shown and described and more particularly pointed out in the claims.

In the drawing wherein like reference characters indicate like or corresponding parts:

Fig. 1 is an elevational view of a time stamp showing a clock face with the stamp in slightly elevated spaced relation above a member normally providing a support therefor;

Fig. 2 is a sectional view along line 2—2 of Fig. 5 3 showing the stamp seated upon the supporting member; and

Fig. 3 is a plan view of the supporting member 10 with a portion broken away to show the construction.

Referring now more particularly to the drawing, the numeral 10 generally designates a device providing an enclosure for an ink pad and a support for a stamp generally designated by the numeral 11.

The device 10 comprises a cup-shaped member 20 consisting of a bottom wall 12 having an upwardly projecting middle portion 13, and a continuous side wall 14. A plate 15, of larger dimensions than the bottom portion 13, is fastened to the latter by screws 16, the projecting edges of the plate forming an upturned flange 17 to provide a receptacle in which an ink pad 18 is mounted and preferably fastened by any suitable adhesive material.

A movable member 19, extending around and in closely spaced relation to the inner surfaces of the side wall 14, provides a seat for the stamp 11. The lower edge of the member 19 is positioned in a recess 20 extending around the support between the side wall 14 and the bottom plate portion 13. The member 19 has a plurality of inwardly projecting lugs 21 underlying the projecting portion of the plate 15.

The upper edge of the member 19 provides a shoulder 22 surrounded by an upwardly and outwardly tapered flanged edge 23 adapted as a guide for positioning the stamp 11 upon the shoulder. The member 19 is supported by a plurality of springs 24 adapted to hold the number 40 in elevated position with the lugs 21 in contact with the plate 15. The springs 24 are sufficiently resilient to retain the member 19 in elevated position under the weight of the stamp 11, in which position the stamp characters are in spaced relation to the ink pad 18. Sufficient clearance space is provided between the member 19 and the bottom wall 12 to permit movement of the member downwardly under pressure exerted on the stamp. The springs 24 are of equal resilience 45 and yield evenly under pressure to permit operative engagement of the impression faces of the stamp characters 25 uniformly with the ink pad 18.

The corners of the supporting device are pro- 55

vided with rounded projections 27 resting upon hemispherical lugs 26 of non-abrasive cushioning material adapting the device to be mounted upon a table top or other finished surface whereby such surfaces are not marred or mutilated in manipulating the stamp.

The stamp normally occupies the position shown in Fig. 2 and thereby serves as a dust-proof cover preventing circulation of air and minimizing the drying of the pad which would otherwise occur by exposure of the pad to the atmosphere.

Thus it will be seen that we have provided an improved combination support and inking device for stamps, the support providing an enclosure for an ink pad and means on which the stamp rests and provides a cover for the receptacle with the stamp characters normally in spaced relation to the pad, said means being yieldable under pressure exerted upon the stamp to bring the stamp characters into even contact with the pad.

Having thus described our invention, it is obvious that various immaterial modifications may be made in the same without departing from the spirit of our invention; hence we do not wish to be understood as limiting ourselves to the exact form, construction, arrangement and combination of parts herein shown and described or uses mentioned.

What we claim as new and desire to secure by Letters Patent is:

1. A device of the kind described comprising a cup-shaped base member, a pad mounted in the base member, a member vertically movable between the pad and the side walls of the cup-shaped member, said movable member normally projecting above the pad with its projecting portion adapted as a seat for a stamp, resilient means providing a support for the movable member, said means yieldable under pressure to permit lowering of the stamp into contact with the pad.

2. A device of the kind described comprising a cup-shaped base member, a pad mounted in said member, a vertically movable member extending around the pad adapted as a seat for a stamp, resilient means providing a support for and normally maintaining the movable member in elevated position wherein a stamp seated thereon is out of contact with the pad, said resilient means yieldable to permit depression of the movable member to bring the stamp into contact with the pad.

3. A device of the kind described comprising a cup-shaped member, a pad mounted in said member, a vertically movable member extending around the pad, a stamp seated on the movable member and forming a cover for the pad, resilient means providing a support for and normal-

ly maintaining the member in elevated position wherein the stamp is in spaced relation to the pad.

4. A device of the kind described comprising a cup-shaped member, a pad mounted in said member, a vertically movable member extending around the pad, a stamp seated on the movable member and forming a cover for the pad, resilient means providing a support for and normally maintaining the member in elevated position wherein the stamp is in spaced relation to the pad, said resilient member being yieldable under pressure exerted on the stamp to permit the stamp to operatively engage the pad.

5. In a device of the kind described comprising a vertically movable member adapted to support a stamp seated thereon, an ink pad circumscribed by said vertically movable member, resilient means normally maintaining said stamp supporting member in a position wherein a stamp seated on said member has its impression face in spaced vertical juxtaposition to the inking face of the pad, said resilient means being yieldable under pressure to permit depression of the stamp supporting member sufficiently to operatively engage the impression face of the stamp with the inking face of the pad.

6. A device of the kind described comprising an ink pad and a vertically movable member adapted to support a stamp seated thereon, a base member providing a support for the pad and stamp supporting member, resilient means normally maintaining said stamp supporting member in a position wherein a stamp seated on said member has its impression face in spaced vertical juxtaposition to the inking face of the pad, said resilient means being yieldable under pressure to permit the stamp supporting member to be lowered to a position wherein the impression face of the stamp operatively engages the inking face of the pad.

7. A device of the kind described comprising an inking pad, a vertically movable member extending entirely around and projecting above the pad to form a seat for a stamp, resilient means providing a yieldable support for and normally maintaining the member in elevated position wherein a stamp seated on the member is in vertically spaced relation to the pad, said resilient means being yieldable under pressure exerted on the stamp to permit operative engagement of the impression face of the stamp with the inking face of the pad, said vertically movable member and said stamp seated thereon cooperating to form a closure preventing circulation of air about the pad, the vertically movable member providing a continuous side wall and the stamp providing a cover for said closure.
